UNITED STATES PATENT OFFICE.

CHARLES B. MARTIN, OF CANTON, OHIO.

MATCH BOX.

Application filed May 18, 1926. Serial No. 109,953.

This invention relates to an improvement in match boxes and aims to provide a match box which contains a supply of ordinary unused or live matches and is also adapted to receive burnt or used matches, thereby relieving persons striking the matches of the necessity of throwing the burnt match on the floor or street if no convenient receptacle therefor is available.

10 A further object is to provide a device of this character which is of simple and durable construction, reliable and effective in operation and easy and comparatively inexpensive to manufacture.

15 Other objects and advantages reside in certain novel features of the construction, arrangement and combination of parts which will be hereinafter more fully described and particularly pointed out in the appended 20 claims, reference being had to the accompanying drawings forming a part of this specification, and in which:—

Figure 1 is a perspective view showing one embodiment of the invention,

25 Figure 2 is a view thereof in longitudinal section,

Figure 3 is a detail view of the blank from which the compartment-forming partition and its attaching means are formed,

30 Figure 4 is a perspective view showing another form of the invention, and

Figure 5 is a view partly in plan and partly in horizontal section further illustrating the form of the invention shown 35 in Figure 4.

Referring to the drawings and more particularly to Figures 1 to 3, inclusive, the numeral 1 designates the tubular casing of a match box in which a tray 2 is slidably 40 fitted in accordance with the usual practice. The present invention proposes the provision of a strip of material, designated generally at S, and which has some degree of resiliency. This material is bent to provide an attaching portion 3 fastened to one of the end walls of the sliding tray. Beyond the attaching portion 3 a strip of material extends over the top edge of the tray and down into the tray to a point adjacent 50 to but slightly spaced from the bottom thereof, the downwardly extending portion of the strip being designated at 4 and serving as a carrier or connecting means for a partition-forming portion 5 which extends along though slightly above the bottom of the tray, as illustrated in Figure 2. The

strip 4 has sufficient resiliency to prevent its formation into the shape shown and yet maintains this shape and tends to maintain its relation to the tray. The attaching portion 3 and the end wall of the tray to which it is connected are provided with registering openings 6 guarded by resilient wings 7 of triangular form, the opening and the wings being conveniently formed by slitting the attaching portion 3 of the strip and the underlying portion of the end wall after the manner of a cross, as shown in the drawing.

In this arrangement there is provided a compartment 7 for the ordinary live matches and a compartment 8 for the burnt or used matches, the burnt or used matches being inserted through the openings 6 and being held against displacement by the wings 7. The wings 7 also insure the extinguishing of the match. This arrangement of strip S presents its body portion to the burnt match being entered through opening 6 thus avoiding engagement of the edges of the strip by the entering match and facilitating the insertion of the match.

In the form of the invention shown in Figures 4 and 5 the tubular casing 1 and the tray 2 are employed as in the other embodiment of the invention but the compartments for the live matches and the used matches are defined in a different manner. As shown in Figs. 4 and 5 a strip S' of material having some resiliency is employed and has an attaching portion 10 suitably fixed as by means of adhesive, riveting or the like, to the inner faces of one of the side walls of the tray adjacent one end thereof. Beyond the attaching portion 10 the strip S' is curved across the tray as shown at 11 and is then extended longitudinally of the tray, as at 12, the portion 12 constituting a partition or a partition-forming member which separates the interior of the tray into a compartment 13 for the live matches and a compartment 14 for the used matches. The end of the tray is provided with an opening 15 guarded by wings 16, the opening 15 being aligned with the compartment 14. The opening 15 and wing 16 correspond in construction to the opening 6 and wing 7. It is to be understood that if desired more than one opening and set of wings may be provided in either or both embodiments of the invention.

In this form also the body portion of the strip S' is presented to the point of the entering match so that said match will push

the strip out of the way without danger of engaging the edge of the strip and thus facilitate the entrance of the match into the compartment intended for it.

5 I claim:—

1. A match box comprising a tubular casing, a tray slideable in said casing, a strip having one end forming an attaching portion and permanently and positively secured to one wall of the tray and also having a partition forming portion extending longitudinally of the tray and spaced from one wall thereof to provide a longitudinally extending burnt match compartment, the other 10 end of the strip being free whereby said partition forming portion is freely movable to vary the size of the compartment formed thereby, said strip extending from one end wall to a point near the opposite end wall of 15 the tray.
2. A match box comprising a tubular casing, a tray slideable in said casing, a strip having one end forming an attaching portion and permanently and positively secured to one end wall of the tray and also having a partition forming portion extending longitudinally of the tray above the bottom thereof and from one side wall to the other, the other end of the strip being free where- 20 25

by said partition forming portion is freely 30 movable to vary the size of the compartment formed thereby in connection with the bottom of the tray, the portion of the strip at the attached end thereof being spaced from the walls of the tray a sufficient distance 35 to provide for the ready insertion of burnt matches without engagement with the edges of the partition.

3. A match box comprising a tubular casing, a tray slideable in the casing and having a bottom wall, side walls, end walls and an open top; and a strip having an attaching portion permanently and positively secured to one wall of the tray and having a partition forming body portion extending 40 longitudinally of the tray to define in connection with one wall of the tray a used match compartment, the end wall of the tray to which the attaching portion of the strip is secured having an opening to permit insertion of used matches into the compartment 45 thereby provided, said strip having its body portion presented to the burnt match opening to facilitate the insertion of burnt matches without their engaging the edges 50 55 of the partition wall.

CHARLES B. MARTIN.
